UNITED STATES PATENT OFFICE.

JEREMIAH H. KATOR, OF DETROIT, MICHIGAN, ASSIGNOR OF ONE-HALF TO WILLIAM A. KIRK, OF DETROIT, MICHIGAN.

RAIL JOINT.

Application filed July 17, 1926. Serial No. 123,093.

This invention relates to rail joints, and the primary object of my invention is to provide rails that may be advantageously used to form a track for the rolling stock of steam and electric railways, the rails being constructed to provide practically continuous rails to eliminate the usual pounding, jarring and noise incident to rolling stock passing over ordinary rail joints. 5 It is a well known fact that the adjacent ends of rails are very often broken down, cracked or otherwise injured by rolling stock passing over such a joint, and very often the wheels and other parts of cars are injured because of excessive stresses and strains incident to the jarring and vibration set up by an ordinary rail joint. The design of my rails is such, that there is an unbroken path for a wheel opposite each joint, and 10 at the joints there is an unbroken support for the ends of rails so that the rail structure is practically continuous throughout its length and insures safe travel as far as the track is concerned.

25 Another object of my invention is to provide a rail structure wherein the web and base of a rail are made of two interlocking parts which materially increase the cross sectional area of a rail web, insure better 30 support for a rail head, and afford spaces in the web of the rail that may be used for other purposes.

A further object of my invention is to provide a two-part railroad rail wherein the parts are separated by members which 35 reduce the noise incident to rolling stock moving on the rail, and these same members may serve as insulators or means of bonding rails, particularly when used in connection 40 with an electric railway.

A still further object of this invention is to provide a strong and durable rail joint wherein positive and reliable means are employed for preventing longitudinal creeping 45 of the rails or ties, sleepers or other rail supports, and provision is made to allow for expansion and contraction of adjoining rail members.

A still further object of this invention is 50 to provide tie plates that may be advantageously used in connection with my rail joint and my rails may be constructed for connection with ordinary rails when such connection is required.

55 Other objects are attained by the novel

construction to be hereinafter specifically described and then claimed, and reference will now be had to the drawing, wherein

Figure 1 is a plan of a portion of a track, with rails partly broken away and partly in 60 section;

Fig. 2 is a cross sectional view taken on the line II—II in Fig. 1;

Fig. 3 is a similar view taken on the line 65 III—III of Fig. 1;

Fig. 4 is a horizontal sectional view taken on the line IV—IV of Fig. 3;

Fig. 5 is a perspective view of a portion of a rail in accordance with this invention;

Fig. 6 is a similar view of a tie plate; 70

Fig. 7 is a perspective view of one end of the rail showing an anti-creeping device;

Fig. 8 is a cross sectional view of a rail showing tie plates or braces that may be used 75 in connection with my rail, and

Fig. 9 is a perspective view showing a portion of an ordinary rail to which may be connected my improved rail.

A rail in accordance with my invention is composed of inner and outer members separately produced and adapted to be placed together to form a continuous rail structure. The outer member comprises a head 1 formed with diverging web portions 2 and lateral base flanges 3, the web portions 2 providing 80 the lower part of the outer rail member with a longitudinal groove or way 4 which tapers inwardly from the bottom of the outer rail members towards the head 1 of said member. 85

The inner rail member is adapted to fit within the groove 4 of the outer rail member and comprises a base portion 5, a web portion 6 and an auxiliary head portion 7, the web portion 6 being formed by concave 90 walls of the inner rail member which afford longitudinal recesses 8 throughout the length of the inner rail member. These recesses confront the web portion 2 of the outer rail member and thus form runways throughout the length of the rail structure. In these runways may be placed solid or tubular members 9 which may be made of various 95 materials for various purposes. For instance the members 9 may be made of rubber for deadening the noise incident to rolling stock moving on the head 1 of the outer rail section, and the tubular rubber members may accommodate electrical connections employed for bonding rails or for transmitting 100

105

110

currents necessary for the maintenance of signal systems in connection with a railroad. The members 9 may be suitable electrical conductors throughout the length of the rail or may be in short lengths simply for bonding purposes at the adjacent ends of rail members.

In laying the track the joints of the outer rail members are placed intermediate the joints of the inner rail members so that there will be a solid rail head 1 over the adjacent ends of inner rail members. This arrangement will afford a solid inner rail member under adjacent ends of the heads 1 and it is in consequence of such alternate arrangement of joints that there will be practically a continuous railway for rolling stock.

In laying the rails on ties, sleepers or other rail supporting members 10 and tie plates 11 are employed for supporting the rail members at any joint, said tie plates being connected to the ties by spikes 12 or other fastening means. Each tie plate is formed with ribs 13 for engaging the lateral base flanges 3 of the outer rail members, and in addition to said tie plates, I may use rail braces 14, as best shown in Fig. 8. These rail braces may be spiked to the ties and engaged under the heads 1 of the outer rail members for firmly supporting said heads, particularly on any curved section of track. The braces 14 may be used as splice bars at the joints of outer rail members, and in some instances the braces may be dispensed with and the lateral flanges 3 spiked to the ties.

To prevent longitudinal creeping of the inner rail members relative to ties or a road bed, one or both ends of each inner rail member may be provided with a depending stud 40 or lug 15 to engage in an opening 16 provided therefor in a tie plate or rail support.

Should it become necessary to connect one

of my improved rails to an ordinary rail 17, said rail may have its head and base cut away to leave a projecting web tongue 18, 45 and an inner rail member may have its ends slotted, as at 19, to receive the web tongue 18, thus connecting an ordinary rail and inner rail member, as shown in Fig. 9, to prevent lateral displacement of one relative 50 to the other. Rail braces may be used at such a joint, and by using rail braces on each tie it is practically impossible for one rail to separate relative to the other, thus eliminating railway accidents because of separating 55 rails.

My rail members may be rolled or otherwise produced and it is thought that the utility of the same will be apparent without further description. While in the drawing 60 there is illustrated the preferred embodiment of my invention, it is to be understood that the structural elements are susceptible of such changes, in size, shape and manner of assembling, as are permissible by the appended claims.

What I claim is:—

1. A rail comprising inner and outer members, one placed on the other and the inner member having concave walls affording 70 spaces between said members, and tubular sound deadening material in the spaces between said members and extending throughout the length of said members.

2. A rail comprising inner and outer members, one placed on the other and the inner member having concave walls affording spaces between said members, the outer member having a head and diverging web portions terminating in lateral base flanges, 80 and sound deadening material in the spaces between said members.

In testimony whereof I affix my signature.
JEREMIAH H. KATOR.
